UNITED STATES PATENT OFFICE.

JOHN F. OHMER, OF DAYTON, OHIO, ASSIGNOR TO OHMER FARE REGISTER COMPANY, OF DAYTON, OHIO, A CORPORATION OF NEW YORK.

FARE-BOX.

1,182,409.

Specification of Letters Patent.

Patented May 9, 1916.

Application filed September 21, 1914. Serial No. 862,686.

To all whom it may concern:

Be it known that I, JOHN F. OHMER, a citizen of the United States, residing at Dayton, in the county of Montgomery and State of Ohio, have invented certain new and useful Improvements in Fare-Boxes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in fare collection boxes of the type shown and described in the patent of Henry F. Fefell, dated June 8, 1915, No. 1,142,244.

The present improvements comprise means for safeguarding the structure from breakage in the operation thereof and from unauthorized manipulation.

The objects of the invention are several: first, to provide means whereby the pawl which closes the lid of the removable fare receptacle is protected from being broken or damaged when the said receptacle is being inserted within the casing; second, to provide means for preventing an element of the lock for the bottom of the casing becoming injured when the removable fare receptacle is being withdrawn from said casing; and third to provide means to prevent the removable fare receptacle being entirely inserted when said fare receptacle is locked. This means also prevents the receptacle-closing means becoming damaged when said receptacle is inserted in the casing in a closed position, and also holds the lid of said fare receptacle open.

Referring to the accompanying drawings, Figure 1 is a front elevation of my improved fare collection box, parts being broken away; Fig. 2 is a section on the line 2—2 of Fig. 1; Fig. 3 is a section on the line 3—3 of Fig. 2; Fig. 4 is a section on the line 4—4 of Fig. 5; Fig. 5 is a section on the line 5—5 of Fig. 4; Fig. 6 is a section on the line 6—6 of Fig. 3; Fig. 7 is an elevation of the lower portion of the fare box showing the fare receptacle in the act of being removed from the casing; Fig. 8 is a perspective view of the receptacle; and Fig. 9 is a perspective view of

one of the locking members of the fare receptacle lid.

Throughout the specification and drawings, 1 represents an upright cylinder or casing which may be mounted on any desirable form of standard (not shown) in a suitable position at the entrance of a car. Mounted on the top of said cylinder 1 is a band or ring 2 in which the ends of a shaft 3 are journaled and on which shaft is mounted a tilting table 4 which is tilted to an open or closed position by a lever 5 mounted on one end of the shaft 3 on the outside of the cylinder 1. (See Fig. 1). The table 4 is under the influence of a spring 6 while a stop 7 is provided at a suitable point to hold said table in a horizontal or closed position against the tension of said spring. The ring 2 is attached to the cylinder 1 by means of a ring 2^a. The attachment of the ring 2^a is such that it cannot be detached from the outside. The fares, either paper or money, fall upon said table 4 as they are deposited through an initial receiver of any well known type, such as the following:—Mounted on the ring 2 is a glass cylinder 8 through which the deposited fares may be viewed on the table 4. On the upper end of the cylinder 8 is a mouth piece 9 provided with an opening 10 into which the fares are dropped. The receiver is provided with a series of deflecting or guide plates 11 which are well known and instrumental in preventing the subsequent withdrawal or removal of the fares from said receiver. The said receiver 8 and the mouth piece 9 are held in position on the ring 2 by vertical bars 12 the ends of which extend between said ring and mouth piece. After the fares have been deposited in said receiver and have been viewed by the conductor to ascertain their genuineness, they may be deposited in the final depository consisting of the removable receptacle 13 below the table 4 by actuating lever 5 to tilt the table 4. The removable receptacle 13 is cylindrical and fits snugly in the bottom of the cylindrical casing 1. The said receptacle 13 is provided with a bottom 14 and a lid 15, said lid being pivotally mounted on a shaft 16 mounted in the sides of said receptacle.

The lid 15 is provided with a spring-lock 17 which cooperates with a lug 18 on the interior of said receptacle in locking the lid

in its closed position. The lock 17 snaps automatically when the lid is moved to a horizontal or closed position. The said lid 15 is further provided with a spring 19 which exerts an influence to open and to hold said lid in an open position. A stop 19^a (Figs. 3 and 6) is provided to limit the opening movement of said lid, and the said lid is further provided with a ratchet disk 20 having a shoulder 21 and mounted on the shaft 16. The disk 20 moves at all times with the lid 15 and is secured to said lid through the agency of a pin 22 which extends through the lid and the hub 23 of the disk (see Fig. 5). The shoulder 21 of the disk 20 is adapted to be engaged by the nose 24 of a pawl 25, pivoted at 26 to a bracket 27 and provided with a spring 28. The bracket 27 is secured to the inner side 20 of the casing 1. The receptacle 13 is held and supported within the casing by a bottom 30 hinged at 31 and provided with a locking lug 32 which co-operates with a key-lock 33 to lock said bottom.

In order to prevent the receptacle 13 from engaging the locking lug 32 when the receptacle 13 is being withdrawn from the casing 1, the hinged bottom 30 is provided with a cam-lug 30^a adapted to be cammed by the receptacle 13 to move the lug 32 out of the path of the said receptacle 13. In order to align the receptacle 13 so that the nose 24 of the pawl 25 will enter the opening 29 in the lid 15 when the said receptacle 35 is placed in the casing 1, the said receptacle is provided with a lug or projection 34 on the outer side thereof adapted to enter an elongated slot 35 in the lower side of the casing 1. The length of the slot 35 is sufficient to permit the complete insertion of the receptacle 13. When the receptacle is inserted in the casing properly, *i. e.*, with the lug 34 in alignment with the slot 35, the lid 15 approaches the pawl 25 with the opening 29 in said lid in alignment with the pawl. It will be apparent that an insertion of said receptacle with the lug 34 out of alignment with the slot 35 will cause said lug 29 to contact with the bottom of the casing 1 and thus the pawl 25 is protected from any jamming by the lid 15. The length of the opening 29 in the lid 15 and the shape of the pawl 25 are such that the receptacle 13 will be prevented from moving to a position 55 which would allow the bottom 30 to be closed unless the said lid is first unlocked, and in an elevated position as shown in Fig. 2. This may be clearly understood from Fig. 4 in which the broken horizontal line 36 represents the top of the receptacle 13 when in position with the bottom 30 closed. However, to provide a further safeguard in opening the lid 15 and to prevent the complete insertion of the receptacle when the 65 lid 15 is closed and locked, a projection 15^a

is secured on the inside of the casing 1, as shown in Fig. 6. This projection 15^a extends over the edge of the receptacle 13 when said receptacle is inserted, and engages the lid 15 to open the same when unlocked, 70 and to hold said lid in an open position. It will also be seen from the dotted or closed position of the lid in Fig. 6, that the said projection 15^a is also instrumental in preventing the complete insertion of the receptacle 13 when said lid is locked in a closed position, thereby preventing the locking of the bottom 30 with the lid closed. When the receptacle 13 is withdrawn from the casing 1, the pawl 25 will rock the lid to a 80 horizontal position at which time it will be locked by the spring-lock 17. The receptacle 13 is, therefore, locked when it is withdrawn thereby preventing unauthorized persons gaining possession of the contents 85 or fares. The receptacle, therefore, can only be opened by authorized persons or those having possession of a key to the lock 17, and it cannot be inserted improperly or in any manner to interfere with a successful 90 and practical operation of the device.

To indicate to the auditor of the company, or other person taking charge of the fares, the number of times the lid of the receptacle has been opened within a given time, 95 and thus informing the person having authority to open the receptacle 13, whether or not access has been had to the receptacle 13 before it was turned over to him, a counter 37 is provided. This counter 37 is 100 mounted on the inside of the receptacle 13 by the aid of a bracket 38 but is viewable through an opening 39 from the outside of the receptacle. The said counter 37 is connected to the lid 15 by a lever 40 and a link 105 41. The arrangement is such that the counter 37 will be actuated to the extent of one digit each time the lid 15 is opened. When the receptacle 13 is delivered to the conductor or is placed within the casing 1, the 110 number indicated by the counter 37 is noted. When the receptacle is again returned to the proper authority, the number is again noted and, in view of the fact that it is only necessary for the lid 15 to be opened once 115 in the meantime, the counter 37 will register only one more digit if the receptacle 13 has not been opened by an unauthorized person. The receptacles 13 of all the fare boxes used on a street railway system are interchangeable; therefore, in order to indicate what receptacle 13 is within a certain fare box, the receptacles are provided with suitable indications 42 which are viewable through a suitable opening 43 in the cylinder 1, and by 120 means of which the removable fare receptacles are kept track of.

Having described my invention, I claim—

1. A casing having a lid closing the lower end thereof, a lock for said lid, a receptacle 130

adapted to be inserted and withdrawn from said casing, and a cam lug on said lid adapted to be engaged by the receptacle when the latter is being withdrawn, whereby the lock for said lid is prevented from being broken through the withdrawal of the receptacle from the casing.

2. A casing, a receptacle adapted to be inserted within said casing, said receptacle having a lid, a lock for said lid, a pawl carried by said casing and adapted to close said lid when said receptacle is withdrawn, means coöperating with said pawl, and a projection carried by said casing and adapted to prevent the complete insertion of said receptacle when said lid is locked and to thereby prevent injury to said pawl and its coöperative elements, said projection also being adapted to open said lid when said receptacle is inserted within the casing and to thereby place it in a condition to be subsequently closed by said pawl and coöperative elements.

**Copies of this patent may be obtained for five cents each, by addressing the "Commissioner of Patents
Washington, D. C."**

3. In combination, a casing, a money receptacle adapted to be inserted therein and withdrawn therefrom having a pivotal lid, a lock for said lid, a pawl mounted on the casing, a cam mounted on the axis of the lid and coöperating with said pawl to close and lock the lid as the receptacle is being withdrawn from the casing, means for ascertaining the opening of the lid after it has been so closed and locked by the withdrawal of the receptacle, and means on the casing to prevent the complete insertion of the receptacle therein when the lid is in a locked condition whereby the lid-opening devices are safeguarded against breakage in inserting said receptacle.

In testimony whereof I affix my signature, in presence of two witnesses.

JOHN F. OHMER.
